UNITED STATES PATENT OFFICE.

WILLIAM T. McGINNIS, OF NEW YORK, N. Y.

AMALGAMATOR.

SPECIFICATION forming part of Letters Patent No. 274,211, dated March 20, 1883.

Application filed December 19, 1882. (No model.)

To all whom it may concern:

Be it known that I, WILLIAM T. McGINNIS, of the city, county, and State of New York, have invented a new and useful Improvement 5 in Amalgamators; and I do hereby declare that the following is a full and exact description thereof, reference being had to the accompanying drawing, and to the letters of reference marked thereon, making a part of this specification.

My invention relates to that class of amalgamators in which gold-bearing sand or pulverized ore is projected into a bath of mercury.

It consists in the combination, with a bent tube or trap containing mercury, of a rotary fan-blower or blast-engine, to which the sand or pulverized ore is delivered by means of the suction created by the engine, and from which it is ejected and forced by the blast through 15 the bent tube and the body of mercury therein contained. The ore enters the mercury from above, on one side, and, passing down through it, emerges therefrom relieved of all its golden particles by reason of their amalgamation with the mercury.

The object of my invention is to produce a compact portable apparatus adapted to the treatment of gold-bearing sand or pulverized ore without the use of water or need of fuel.

In the accompanying drawing, which is a side elevation, partly in section, of my apparatus in portable form—

A represents a bench or stand; B, an upright secured thereto; C, a rotary blower or blast-fan of any approved pattern, secured to and supported by the upright B, and which is capable of producing a strong suction on the inlet and a blast upon its outlet side. This blower may be driven by hand-power in the 35 portable machine; or upon a larger scale by any suitable motor.

D is a tube connected to the outlet-port of the blower and bent to form a trap or U-shaped bend. This tube is supported by the bench A, its bend being carried below the same and its discharge end carried up to a point on a level with or slightly above the blower C.

E represents a funnel connected with a lateral feed-tube controlled by a cock, F, and connected with the bent tube for supplying the same with mercury as required.

To the inlet-port of the blower a suction-

tube, G, may be connected, to extend to the bank or pile of sand or ore to be treated. This tube may be made long and flexible to 55 reach different portions of the pile.

The lower end of the band which forms the amalgamating-chamber of the apparatus is fitted with a cock, H, through which the amalgam is drawn off.

In the use of the apparatus the bend of the tube D is filled with mercury, K, until it has risen in each arm and completely sealed said bend. The blower is now set in motion by hand or by power and the ore fed thereto 65 either by means of the suction created in the tube G or by means of a hopper communicating with the inlet-port of the fan. The sand or ore thus supplied to the blower is carried forward into the tube D, and forced by the 70 pressure of the blast through the bath of mercury at K, which will operate to take up and amalgamate the particles of gold thus brought into contact therewith, leaving the waste ore to be carried off and discharged from the end 75 of the tube.

I am aware that a stream of ore and mercury have been made to travel together through a tube or cylinder by means of an exhaust of air effected at the discharge end of the tube, 80 and that in such form of apparatus a bent tube has been employed, in which a body of mercury is collected, through which the ore is made to pass under the influence of atmospheric pressure by reason of the exhaust in 85 the outer end of the tube. I am also aware that the amalgamation of comminuted ore has been attempted by forcing it down by means of compressed air into a bath of molten lead. My invention differs from these in that it relates to a novel apparatus in which the dry ore is driven forward by a powerful blast of air into and out of a body of mercury, whereby its amalgamation is secured without the need of water or of fuel, and with greater rapidity, 90 and, as I claim, with greater efficiency and at less cost than by the means and processes heretofore employed, as above stated, and with the advantage, moreover, of entire portability and of being ready for work in localities where, 100 from the absence of water and fuel, other appliances are useless.

I do not claim as new the use, in an amalgamating apparatus, of a bent tube as a mercury-

holder, nor of an ore-hopper in combination with a bent tube, nor drawing the ore through a body of mercury held in suspension by means of suction exerted above the body of the mercury, as set forth in Letters Patent No. 212,644, dated February 25, 1879, nor forcing the ore through a bath of molten lead, in manner as set forth in Letters Patent No. 59,955, dated November 27, 1866; but

10 I claim as new and desire to secure by Letters Patent—

In an apparatus for the amalgamation of comminuted ore or ore-bearing sand, the combination, with a conduit for the supply of the ore, and with a bent tube adapted to be sealed by a charge of mercury placed therein, and

fitted with a discharge-pipe extending upwardly therefrom, of a fan or blower connected with the supply-conduit upon the one side and with the inner end of the bent tube on the other, and operating to deliver and drive the ore from the conduit into and through the tube, substantially in the manner and for the purpose herein set forth.

In testimony whereof I have signed my name to this specification in the presence of two subscribing witnesses.

WILLIAM T. McGINNIS.
